CONTROLLING DEVICE FOR SAND-BLAST APPARATUS.

1,172,008.

Specification of Letters Patent. Patented Feb. 15, 1916.

Application filed January 31, 1914. Serial No. 815,611.

To all whom it may concern:

Be it known that we, FREDERICK A. COLEMAN, DAVID S. HAWKINS, and ALBERT J. FARRELL, each a citizen of the United States, 5 and residing the first at Gates Mills and the last two at Cleveland, each in Cuyahoga county and State of Ohio, have invented a certain new and useful Improvement in Controlling Devices for Sand-Blast Apparatus, of which the following is a full, clear, and exact description, reference being had to the accompanying drawings.

This invention is for a device for controlling the flow of sand and air in a sand blast 15 apparatus.

An object is to provide a device by which the flow of sand and air may be controlled from one point and in very simple manner, thus avoiding the use of the usual plurality 20 of inconveniently separated valves for controlling the sand blast apparatus.

Another object is to so arrange the device 25 that the flow of sand from the reservoir may be controlled by a valve controlling the air to counteract the pressure on the sand in the sand conduit, and so arranged that the counteracting air may be directed by such controlling means to clean out the hose and a valve in the sand blast passage before the 30 closing movement of this valve is started.

Another object is to provide a means in 35 an air passage for regulating the proportion of sand and air in the sand blast, and still another object is to provide for shutting off the sand blast without lowering or materially changing the pressure in the sand tank.

The drawings show a preferred form of 40 the device embodying the invention which is hereinafter more fully described in connection therewith, and the essential characteristics are hereinafter set forth in the claims.

In the drawings Figure 1 is a side elevation 45 of the pipe connections leading to and from the sand tank; Fig. 2 is a vertical section taken substantially on the axis of the valve plugs; Fig. 3 is a vertical section taken on the line 3—3 of Fig. 2; Fig. 4 is a substantially horizontal section taken on the line 4—4 of Fig. 2 showing the valve for regulating the flow of air through the device; Fig. 5 is a fragmentary section taken on the

same plane as Fig. 2 showing one of the valve parts in another position; Fig. 6 is a 55 transverse section taken on the line 6—6 of Fig. 2; Fig. 7 is a transverse section taken on the line 7—7 of Fig. 2; Fig. 8 is a sectional detail taken on the line 8—8 of Fig. 2, showing the lugs between the two valve 60 plugs.

Referring to Fig. 1, 10 indicates the usual sand tank to which leads an air pipe 12 connected with a suitable source of pressure fluid supply. This pressure fluid is hereinafter referred to as air. The bottom of the tank 10 is funnel-shaped as at 14, in the usual manner, and leading from the bottom is a pipe 15 through which the sand flows to a pipe 16 leading to our controlling device, 70 shown at 18. Leading from the air pressure line 12, is a branch passage or pipe 19 opening into the controlling device, through which the air which is mixed with the sand providing the sand blast is supplied. 20 75 indicates a pipe leading from the controlling device and to which the usual hose is connected for leading the sand blast to the desired point. 22 indicates a suitable hand lever which may be moved through a half 80 revolution to operate the valves of the device, as will be hereinafter described. 23 is a valve for shutting off the supply of air 85 from the sand tank before filling the same.

Mounted in the upper portion 25 of the casing of the controlling device is a transverse rotatable valve plug 28 having an opening 29 therethrough communicating with a vertical passage 30 leading upwardly from below the casing and through which the sand blast passes. The plug 28 has projections 32 on its inner end adapted to be engaged by 95 projections 33 on the adjacent end of a second rotatable valve plug 35. These projections are so arranged that the plug 28 is rotated one-quarter turn by a one-half rotation given to the plug 35. On the opposite 100 end of this valve plug is a cylindrical portion 36 over which is fitted an eye 37 of a crank arm 22, which is secured in place by a suitable nut 38. Both of these valve plugs are fitted into a tapered bore and the plug 105 35, last described, is drawn to its seat by the

action of the nut 38, the eye 37 of the crank arm bearing only on the portion of the casting surrounding the plug, as at 40. The valve plug 28 is held to its seat by a screw 42 mounted in a cap 43 and adapted to be locked in the desired position by a locknut 44. The cap 43 has an inwardly projecting flange internally threaded at 46 to cooperate with external threads on a flanged portion 47 of the casing. The cap itself is prevented from turning by means of a pointed set screw 48 adapted to engage the flange 47, and be locked in engagement with a suitable nut 49.

10 The upper portion 25 of the casing is provided with a horizontal flange 50 adapted to rest on a similar flange 51 on the lower portion 54 of the casing. These flanges are provided with suitable outwardly extending ears 55 through which are made bolt holes 56 adapted to receive the bolts 57 by which the two portions of the casing are secured together. A layer of suitable packing 58 is provided between the two portions of the casing to make them thoroughly air tight.

15 A circular eddy chamber 60 in the lower casing opens upwardly into the passage 30 of the upper casing. The sand is brought up into this eddy chamber, where it is mixed with the air, as will be hereinafter described, through a short tube 62 rigidly mounted in a contracted portion 63 beneath the eddy chamber. This tube communicates at its lower end with the pipe 16 leading from the sand tank. The passage from the pipe 16 to the pipe 62 is made funnel-shaped, as shown at 65, to provide for the sand passing readily into the pipe 62.

20 When in operation, the sand is mixed with the air at the upper portion of the eddy chamber 60 and the blast passes upwardly through the passage 30 and the opening 29 in the valve plug 28 and out through the pipe 20. The air which mixes with the sand is brought into the lower side of the eddy chamber 60 through a passage 68, which communicates with a passage 70 extending downwardly from the lower side of the seat of the valve plug 35. This valve plug is hollow, as shown, and the air is brought into it through the pipe 19, which is threaded into a boss 72 extending outwardly from the side of the casing adjacent the valve plug 35. From this pipe the air passes into the interior of this valve plug, through the opening 73 and then passes from the interior of the plug to the passage 70 through an opening 75 in the side of the plug. The two valve plugs are shown in their operative position in Fig. 1. That is, with the opening 29 in alignment with the passage 30, the opening 73 communicating with the pipe 19, and the opening 75 registering with the passage 70.

With the parts in this position, the air from the pipe 19 is directed through the passages just described to the eddy chamber 60, where it swirls around the annular space outside of the pipe 62 and then passes upwardly through the passage 30 carrying with it the sand, which is fed upwardly, through the pipe 16 and the tube 62, by means of the pressure within the sand tank. This thoroughly mixes the sand with the air and produces the desired sand blast.

To control the amount of air mixed with the sand in the eddy chamber and thereby regulate the proportionate amounts of sand and air in the sand blast, we provide a suitable valve plug 76 having an opening 77 therethrough adapted to register with the passage 70 or be turned transversely of this passage, entirely closing the same. This plug is provided with a suitable thumb piece or wing 79 outside of the casing, by which it may be rotated to regulate the flow of air. A projecting finger or pointer 80 (Figs. 1 and 4) stands over an arcuate boss 82 on the side of the casing. This boss may be suitably marked or graduated to indicate different proportionate mixtures of sand and air.

When it is desired to stop the operation of the sand blast, it is only necessary to rotate the hand lever 22 through a half revolution, which, as shown in the drawing, would be to move it from the position shown in Fig. 3 to the vertical position shown in Fig. 1, and then to the horizontal position opposite that which it holds during the operation of the sand blast. This operates the valves in the following manner: the first quarter rotation of the lever 22 moves the valve plug 35 through a quarter rotation, but does not move the plug 28. This moves the opening 73 in the plug 35 away from a small air chamber or passage 85 in the boss 72, through which the air passes to the interior of the plug 35. On this movement the opening 75 is moved into communication with this small chamber 85, thereby closing the passage 70 and directing the air, which enters the plug through the opening 75 through an opening 88 in the plug, into a passageway 89 which opens into the passageway 30. The position of the openings after this quarter rotation is shown in Figs. 5, 6 and 7, (the direction of the air being indicated by the arrow in Fig. 5).

The effect of stopping the passage of air through the passages 70 and 69 and directing it through the passage 89 to the passage 30 brings the air above the chamber where the sand is mixed with the air and causes a back pressure on the sand sufficient to stop its flow. At the same time the air entering through the passage 89 passes upwardly through the plug 29 and out

through the pipe 20, cleaning the passage for the sand blast clear to the nozzle almost instantaneously.

The further movement of the lever 22 rotates the plug 35 to a position which closes the passage 89, the passage 70 still remaining closed, thus shutting off the passage of air through the pipe 19. After the quarter turn of the plug 35 the lugs 33 engage the lugs 32, as shown in Fig. 8, and on the next quarter turn rotate the plug 28 therewith, which throws the passage 29 transversely of the passage 30 closing the same and preventing the escape of sand or air from the sand tank. This, however, does not affect the pressure of air in the pipe 12 and by thus closing the passage 30, the pressure in the tank is maintained, which allows the blasting operation to be resumed at once upon a reverse movement of the lever.

In closing off the sand blast it is well to make a slight pause with the lever in the vertical position, shown in Fig. 1, and the valve plug 35 in the position shown in Fig. 5, equalizing the pressure in the sand tank thereby stopping the flow of sand and cleaning the passages and the valve 28 of any particles of sand that may have lodged therein. This provides for the closing movement of the plug 28 occurring only when the passage is entirely free of particles of sand, thus very greatly prolonging the life of this valve. This pause at the same time allows the air entering through the passage 89 to entirely clean the entire passage including the hose, of all sand, blowing the same from the blast nozzles before the lever is moved the second quarter rotation closing the valve 28 and the air passages, as described.

To prevent the sand wearing away the interior of the casing above the mixing chamber 60, we provide a lining or bushing 90 of soft resilient material such as soft rubber, which experience has demonstrated, resists the wearing action of the sand very effectively.

It will be seen from the foregoing description that we have provided a sand blast controlling device which is so arranged that the flow of sand is controlled by the action of the air and the air which is used to stop the flow of sand also acts to clean the sand blast passages and the valve therein. Accordingly, none of the valve bearings of our device will be worn by the action of the sand, as no sand passes through the valves controlling the air and the valve in the sand blast passage is automatically cleaned by the air before its closing movement is started.

Having thus described our invention, what we claim is:

1. The combination of a sand tank, a source of pressure fluid supply, a conduit therefrom to the sand tank, a sand conduit

leading from the tank, means for directing pressure fluid from the source of supply to the last named conduit against the pressure in the tank, thereby balancing the same and stopping the flow of sand, means for thereafter closing the sand conduit at a point removed from the point where the sand is stopped, and an operating device common to both of the last mentioned means and adapted to operate the same in their proper order in respect to time.

2. A controlling device for a sand blast apparatus comprising a mixing chamber, a conduit for sand leading to said mixing chamber, an air passage leading to said mixing chamber, a conduit for the sand blast leading from said mixing chamber, an air passage leading to the sand blast conduit, a valve adapted to direct air to either or both of said air passages, a valve in the sand blast conduit, and a connection between said valves whereby the latter may be operated consequent upon the movement of the first mentioned valve.

3. In a sand blast apparatus, the combination, with a sand tank, a source of pressure fluid supply, a conduit leading therefrom to the sand tank and a conduit for the sand leading from the sand tank, of a controlling device having a mixing chamber into which said conduit for sand opens, a conduit for pressure fluid leading from the source of pressure fluid to the controlling device, the controlling device having a pressure fluid passage therein leading to the mixing chamber, a passage therefrom for the sand blast, a passage leading to the sand blast passage at a point separated from the mixing chamber, a valve adapted to direct pressure fluid to either of these passages whereby the sand may be mixed with the pressure fluid or the flow thereof may be stopped by counteracting the pressure which forces it through the sand conduit, a second valve in the passage for the sand blast, and connecting members between said valves whereby the last named valve is operated by the movement of the first mentioned valve.

4. In a sand blast apparatus, the combination with a source of pressure fluid, a sand tank and a conduit thereto from the source of pressure fluid and a conduit for the sand leading from the sand tank, of a controlling device comprising a mixing chamber into which the conduit for sand opens, a passage for the sand blast, a passage for pressure fluid leading to the mixing chamber, a passage leading to the sand blast conduit ahead of the mixing chamber, a valve directing the pressure fluid to either of said passages, a conduit leading from the source of pressure fluid to the controlling device and communicating with said valve, a second valve in the sand blast conduit, connections between said valves, and means for operating the first

- mentioned valve whereby the pressure fluid is shut off from the passage leading to the mixing chamber and directed to the sand blast conduit thereby counteracting the pressure on the sand in the sand conduit and a further movement of said valve operates to shut off the pressure fluid from the source of supply at the same time closing the valve in the sand blast conduit.
- 10 5. A controlling device for a sand blast apparatus comprising a mixing chamber, a sand tank, a conduit for sand leading to said mixing chamber, an air passage leading to said mixing chamber, a conduit for the sand blast leading from the mixing chamber, means for regulating the flow of air to the mixing chamber, a valve in the sand blast conduit on the side of the mixing chamber remote from said sand tank, means for creating a preponderance of pressure between the valve and the tank in the sand conduit forming a back pressure whereby the flow of sand is stopped and at the same time the sand blast conduit is cleaned, and means for 25 thereafter closing the valve in said conduit.
6. In a sand blast apparatus, the combination of a conduit for the sand and a conduit for air, a controlling device comprising a casing to which each of said conduits leads, 30 a mixing chamber in said casing, a passage for air leading to said mixing chamber within the casing, a passage for the sand blast leading through said casing, a second passage for air leading to said sand blast passage ahead of the mixing chamber, a valve plug in the casing having openings communicating with the passage leading to the mixing chamber and passage leading to the sand blast passage, said openings being so 35 arranged that when one of these is closed the other is open, means for moving said valve plug to shut off the passage leading to the mixing chamber and allow air to pass to the conduit for the sand blast, thereby 40 counteracting the pressure of the sand, stopping the flow thereof and at the same time cleaning the passage for the sand blast, a valve plug in said passage for the sand blast, a connection between said plug and the first 45 mentioned plug whereby the last named plug may be rotated after the flow of sand is stopped and the passage is cleaned.
- 50 7. A controlling device for a sand blast apparatus comprising a casing having therein a mixing chamber to which the sand conduit leads, a passage leading from said mixing chamber, a rotatable valve plug, a conduit for air leading to the casing and adapted to be closed by said valve plug, a passage 55 leading to the mixing chamber adapted to be closed by said valve plug, a valve plug adapted to close the passage for the sand blast, said plug being in alignment with the first mentioned plug, and means for rotating both plugs.

8. In a controlling device for a sand blast apparatus, the combination of a casing having therein a mixing chamber, a passage for the sand blast leading therefrom through the casing, a conduit for air leading to the 70 casing, a rotatable valve plug closing the conduit for such air, a passage for air leading from the valve to the mixing chamber, a second passage for air leading from the valve to the sand blast conduit, a second 75 valve plug closing the sand blast passage, tapered seats in which said valves are mounted, operative connections between said valves, means for keeping the valves seated, and means for rotating the first mentioned 80 valve plug whereupon the second named plug is later rotated by said connections.

9. A controlling device for a sand blast apparatus comprising a casing having a mixing chamber through which the sand 85 conduit leads, a short tube projecting upwardly in said mixing chamber through which the sand passes, an annular passage for air around said projection, and a passage for air leading to said mixing chamber 90 at the lower portion thereof, a passage for the sand blast, a passage for air leading to the sand blast passage above the mixing chamber, and means for closing the air passage to the mixing chamber and opening the air passage to the blast passage to stop the flow of sand and clean the sand blast passages.

10. A controlling device for a sand blast apparatus comprising a casing having a 100 mixing chamber through which the sand conduit leads, a short tube projecting upwardly in said mixing chamber through which the sand passes, an annular passage 105 for air around said projection, and a passage for air leading to said mixing chamber at the lower portion thereof, a passage for the sand blast, a valve in said sand blast passage, a passage for air leading to the sand blast passage above the mixing chamber, means for closing the air passage to the mixing chamber and opening the air 110 passage to the sand blast passage to stop the flow of sand and clean the sand blast passage, and means for closing the sand blast passage by moving the first mentioned 115 means.

11. In a device for controlling a sand blast apparatus, the combination of a casing 120 into which the sand enters at one end, a passage for the sand blast leading through the casing, a mixing chamber at one end of said passage, an air passage within the casing leading to the mixing chamber, and a second air passage leading to the sand blast 125 passage ahead of the mixing chamber, a valve plug lying transversely of the sand blast passage, a hollow valve plug adapted to close and open each of said air passages, an air chamber at one side of said plug, the 130

plug having openings each adapted to communicate with said last mentioned chamber when the plug is in different positions, a means for rotating said plug, and connections between said plug and the first mentioned plug whereby the latter plug is rotated.

12. In a sand blast apparatus, the combination of a tank, a source of pressure fluid supply, a conduit therefrom to the tank, a conduit for sand leading from the tank, a mixing chamber in said last named conduit, means for bringing pressure fluid to said mixing chamber, a valve controlling the mixture, a valve for closing the sand conduit connected with the first valve, a passage from the first valve to the sand conduit between the valve in the conduit and the tank, and means for operating both of said valves to direct air to the mixing chamber or to the sand conduit between the valve and the mixing chamber to balance the pressure in the tank and stop the flow of sand and thereafter close the valve in the sand conduit.

13. In a sand blast apparatus, the combination of a sand tank, means for supplying pressure fluid thereto under a constant pressure, a conduit for sand leading from the sand tank, two passages for pressure fluid, one of said passages being arranged to enter the conduit so as to mix with the sand and force the same away from the sand tank and

the other of said passages so entering the conduit that a portion of the pressure fluid flowing therethrough tends to flow toward the sand tank so that it may counterbalance the pressure forcing the sand along the conduit and stop the flow of sand, valve means for controlling each of said passages, and a common operating device for said valve means.

14. In a sand blast apparatus, the combination of a sand tank, means for constantly supplying pressure fluid thereto, a sand blast conduit leading from the sand tank, a valve in said conduit, a mixing chamber in said conduit, a passage for pressure fluid leading to said mixing chamber, a passage for pressure fluid leading to said conduit between said valve and the sand tank, valve means for controlling said passages to open either or close both of the passages at one time, a single operating means for said valve means, and means operatively connecting the valve means with the valve in the sand blast conduit.

In testimony whereof, we hereunto affix our signatures in the presence of two witnesses.
